UNITED STATES PATENT OFFICE

104,494

DESIGN FOR A TEXTILE FABRIC

Curt E. Forstmann, Montclair, N. J.

Application July 24, 1936, Serial No. 64,019

Term of patent 14 years

To all whom it may concern:

Be it known that I, Curt E. Forstmann, a citizen of the United States, residing at Montclair, in the county of Essex and State of New Jersey, have invented a new, original, and ornamental Design for a Textile Fabric, of which the following is a specification, reference being had to the accompanying drawing, forming part thereof.

In the drawing, the sole figure is a plan view of a piece of the textile fabric embodying the design of the present invention.

The design comprises rows of diamond-shaped figures sheared in the nap of the material arranged in diagonal relation and having ragged edges due to the fleecy nature of the fabric.

I claim:

The ornamental design for a textile fabric as described and as shown.

CURT E. FORSTMANN.
